UNITED STATES PATENT OFFICE.

CLEOPHAS A. TOUPS, OF HOUMA, LOUISIANA.

DESIGN FOR A HOE.

SPECIFICATION forming part of Design No. 33,378, dated October 16, 1900.

Application filed September 25, 1900. Serial No. 31,107. Term of patent 14 years.

To all whom it may concern:

Be it known that I, CLEOPHAS A. TOUPS, a citizen of the United States, residing at Houma, in the parish of Terre Bonne and State 5 of Louisiana, have invented and produced a new and useful Design for Hoes, of which the following is a specification.

My invention relates to a new and useful design for hoes.

o In the drawings which accompany this specification and of which they form a part, Figure 1 is a plan view of my design. Fig. 2 is a side elevation of the same.

As shown in the drawings, my design consists of the diverging sides 1, the rib 2, beveled at 3, branching at 5, and curved outward and around, partially encircling the eye 4 and enlarged at 6, and the eye 4, which is frustoconical in outer contour and the top of which

is formed of the alternate curves 7 and 8, of 20 single and double curvature, respectively. The bit of the hoe is beveled at 9 and uniformly curved at 10.

The material or essential feature of my design is the sharply-divergent sides 1 and the 25 rib 2, as described.

Having described my invention, what I claim as new, and wish to secure by Letters Patent, is—

The design for a hoe, as herein shown and 30 described.

In testimony whereof I have hereunto set my hand in presence of two subscribing witnesses.

CLEOPHAS A. TOUPS.
